UNITED STATES PATENT OFFICE.

JOHN B. GABE, OF SWANSEA, ENGLAND.

DESIGN FOR A THERMOMETER-CASE.

SPECIFICATION forming part of Design No. 30,225, dated February 21, 1899.

Application filed November 19, 1898. Serial No. 696,938. Term of patent 14 years.

To all whom it may concern:

Be it known that I, JOHN BERNARD GABE, a subject of the Queen of Great Britain, residing at Morriston, R. S. O., Swansea, in the county of Glamorgan, England, have invented and produced a new and original Design for Thermometer-Cases, of which the following is a full, clear, and exact description, reference being had to the accompanying drawings, forming part thereof.

My new design is illustrated in the accompanying drawings, in which—

Figure 1 is a face view, and Fig. 2 an edge or side view, of the thermometer-case.

a is the thermometer-case, *a'* the cap or cover, and *b* is a portion which may be used as a tongue-depressor and which may be also used as a handle for swinging the case containing the instrument.

Having described my invention, what I claim as new, and desire to secure by Letters Patent, is—

The design for a thermometer-case, as herein shown and described.

J. B. GABE.
